UNITED STATES PATENT OFFICE.

PIOTR WARMINSKI, OF BALTIMORE, MARYLAND.

PROJECTILE AND CANNON.

1,269,884.

Specification of Letters Patent. Patented June 18, 1918.

Application filed January 19, 1918. Serial No. 212,600.

To all whom it may concern:

Be it known that I, PIOTR WARMINSKI, a citizen of Russia, residing at Baltimore, in the county of Baltimore and State of Maryland, have invented certain new and useful Improvements in Projectiles and Cannon, of which the following is a specification.

The primary object of my invention is the provision of a cannon especially adapted for firing an explosive torpedo of a certain design, the arrangement being such that the torpedo is adapted for a succession of explosions whereby one explosion may occur outside of a ship and another within the hull thereof.

A further object of the invention is the provision of a torpedo adapted to travel in a straight line through the water and constructed to explode upon striking the enemy ship, thereby permitting an auxiliary explosive portion of the projectile to readily enter the ship for exploding interiorly thereof.

A still further object of the device is to provide a double torpedo adapted for successively timed explosions and a cannon adapted for projecting the torpedo and having a breech firing mechanism for accommodating the device during the firing operation.

30 In the drawing forming a part of this application and in which like reference characters designate corresponding parts throughout the several views.

Figure 1 is a central longitudinal sectional view through the device;

Fig. 2 is a top plan view thereof;

Fig. 3 is a transverse sectional view of the same taken upon enlarged scale; and

Fig. 4 is a central longitudinal sectional view of the torpedo partially broken away.

The torpedo 10 of my construction consists of a substantially cartridge-shaped casing 11 having a chamber 12 therein for holding dynamite or other explosive material 13, 45 a cap 14 being screw-threaded into the base of the casing to close the chamber. A firing pin 15 projects forwardly of the tapered nose 16 of the casing 11 with its inner end normally spaced from a fulminating cap 17 located in the forward end of the chamber 12 and adapted for igniting the dynamite 13 when the pin 15 penetrates the said cap upon contacting an object.

A tubular tail 18 of spiral arrangement is 55 carried by the cap 14 extending axially rearwardly of the casing 11 being designed to

hold a charge of explosive material 19. A fuse 20 extends through a plug 21 between the dynamite 13 and the explosive material 19. It will be understood that when the torpedo 10 is projected through the water, the spiral tail 18 holds the same upon a straight course of travel. When the pin 15 strikes a ship, the dynamite 13 will be exploded, making a hole in the ship through which the cap 14 and the tail 18 will enter and the fuse 20 becoming ignited, will fire the explosive 19 at a point within the ship, thereby further damaging the ship.

My form of cannon 22 is especially designed for firing the torpedo 10 and comprises a barrel 23 having a bore 24 for receiving the casing 11 while the breech portion 25 of the gun projects rearwardly from the barrel 23 and has a bore 26 for the accommodation of the torpedo tail 18.

An enlarged portion 27 of the breech bore 26 contains a suitable charge of explosive material 28 for projecting the torpedo 10 as may be found desirable.

The lower or base portion 29 of the breech 25 is integrally formed with the barrel 23 while the upper half 30 of the breech is hingedly connected as at 31 with the lower half thereof. Suitable retaining and locking latches 32 are provided between the two portions 29 and 30 of the breech 25, whereby the breech may be maintained closed with the torpedo 10 and the charge 28 secured therein when the cannon is loaded. An exploding 90 member 33 such as a spark or firing plug extends through the breech member 30 having electric circuit wires 34 leading thereto, whereby the charge 28 may be exploded at any desired distance from the cannon 22, 95 though it will be obvious that any other form of exploding member for the charge 28 may be employed if desired.

The complete operation of the device will be at once apparent from this detailed description of the torpedo 10 and the cannon 22 and the operation of each of the same, it being seen that the breech 25 is readily opened by releasing the latches 32, a handle 36 being provided upon the breech member 30 for 105 swinging the same upon its hinges 31. A serviceable destroying means is provided which is especially adapted for submarine destroyers as the torpedo 10 may be projected in a straight course through the water 110 for penetrating a submarine and destroying the same.

What I claim as new is:—

1. A device of the class described comprising in combination with a cannon having a barrel and a breech extension arranged with a bore, a torpedo comprising a casing positionable within the cannon, an explosive spiral steering tail upon the torpedo adapted for arrangement within the bore of the breech during the firing operation, the torpedo being provided with a chamber therein adapted for receiving an explosive material, a fuse between said chamber and the interior of the tail, and a firing pin at the nose of the torpedo.
- 15 2. A torpedo comprising a cartridge-shaped casing having a chamber therein, an explosive cap at the forward end of the chamber, a firing pin for said cap at the forward end of the casing, a threaded closure at the base end of the casing, a spiral tail centrally projecting from said closure axially of the torpedo arranged with an explo-
- 20

sive chamber therein, and a fuse carried by said closure having its opposite end arranged within the casing and tail.

25

3. A torpedo comprising the substantially cartridge-shaped casing having a chamber therein, an exploding cap at the forward end of the casing, explosive material within said chamber, a firing pin for said cap carried by the forward end of the casing, a closure for the rear end of the casing, a spiral-shaped steering tail projecting from said closure having a chamber therein communicating with the interior of the casing, explosive material within the chamber of said tail, a threaded plug carried by the closure between the chambers of said casing and tail, and a fuse projecting through said plug contacting the explosive material within the said chambers and whereby the casing and tail are adapted for successive explosions.
